UNITED STATES PATENT OFFICE.

CHARLES W. ARMBRUST, OF CHICAGO, ILLINOIS, ASSIGNOR, BY MESNE ASSIGNMENTS, TO THE AMERICAN BRAKE SHOE & FOUNDRY COMPANY, OF WILMINGTON, DELAWARE, A CORPORATION OF DELAWARE.

BRAKE-SHOE.

1,239,446.

Specification of Letters Patent. Patented Sept. 11, 1917.

Continuation in part of application Serial No. 79,237, filed February 19, 1916. This application filed April 17, 1916. Serial No. 91,624.

To all whom it may concern:

Be it known that I, CHARLES W. ARMBRUST, a citizen of the United States, residing at Chicago, in the county of Cook and 5 State of Illinois, have invented a certain new and useful Improvement in Brake-Shoes, of which the following is a full, clear, concise, and exact description, reference being had to the accompanying drawings, 10 forming a part of this specification.

My invention relates to brake shoes and has for its object the provision of an improved back for brake shoes which has advantages in construction and cheapness in 15 the manufacture thereof.

My invention contemplates in its preferred form the provision of a plurality of fingers preferably drawn from the material of the back, which fingers coöperate to form 20 a key lug.

My invention herein, more particularly as relating to Figures 4 and 5 is a continuation in part of my prior application Serial No. 79,237, filed Feb. 19, 1916.

25 I will explain various forms which my invention may take more in detail by referring to the accompanying drawing illustrating the same, in which

Fig. 1 is a top view of a blank for a back; 30 Fig. 2 is a perspective view showing the blank as formed into a finished back;

Fig. 3 is a top view of a modified form of blank, and

Fig. 4 is a perspective view of the blank 35 of Fig. 3 in its finished form.

Referring more particularly to Figs. 1 and 2, I show a blank having the body portion 1 from which four fingers 2, 3, 4 and 5 are adapted to be drawn to form the key lug 40 as shown more clearly in Fig. 2. Openings 6 and 7 are left so that metal of the shoe may flow therethrough to securely hold the back and shoe together. Holes 8 are provided in the fingers to permit the body metal 45 to flow therethrough and anchor the body and back together and prevent endwise movement of the fingers. The fingers are provided with coöperating notches 9 and 10 respectively which form the key slot. When 50 drawn into the condition of Fig. 2 I have thus provided a key slot in which the lug is divided both transversely and longitudi-

nally. A longitudinal opening is provided for the key. A transverse strip of metal 11 extends across the back to strengthen it and 55 a longitudinal strip of metal 12 extends throughout the entire length of the back for strengthening purposes. The back is thus braced both longitudinally and transversely and is provided with apertures to adequately 60 permit of solid union between the back and the shoe. The longitudinally aligned parts of the lug may of course abut if so desired.

In Figs. 3 and 4, I show a modified form in which the back portion 15 has the holes 65 16 through which metal may pass to secure a proper union between the back and the shoe and in which the key lug is formed of two fingers 17 and 18 drawn transversely out of a portion of the metal of the back 70 and from extending metal. Holes 19 are provided in the fingers to permit metal to pass therethrough for holding purposes. The fingers 17 and 18 are drawn substantially as shown in Fig. 5 to form the finished 75 back.

From what has thus been described the nature of my invention will be readily clear to those skilled in the art. Having however thus described one form which my invention may take, what I claim as new and desire to secure by Letters Patent is:

1. A back for a brake shoe having a plurality of pairs of longitudinally extending straps of material stamped therefrom to 85 form a holding lug for said back.

2. A back for a brake shoe provided with a double lug, said lug comprising four tongues, two tongues being drawn from each end to a point at or adjacent the center of 90 said back.

3. A back for a brake shoe provided with four lugs, said lugs each being formed of tongues drawn from the ends of said back to a point adjacent the center of said back. 95

4. A back for a brake shoe provided with a double lug, said lug comprising four tongues drawn longitudinally from said back.

5. A back for a brake shoe having two 100 pairs of transverse lugs separated longitudinally of the shoe and transverse and longitudinal straps integral with said back located between the parts of said lugs.

6. A back for a brake shoe having a four part key lug being stamped from the body of the back and the four parts of said lug cooperating to provide a key slot.
- 5 7. A back for a brake shoe having a four part key lug consisting of two pairs of tongues stamped from the body of the back.
- 10 8. A back for a brake shoe having a four part key lug, the four parts of said lug being stamped from the body of the back separated transversely and longitudinally.
- 15 9. A back for a brake shoe having a four part slotted key lug consisting of tongues stamped from the body of the back.
- 20 10. A back for a brake shoe having an undetached strap running centrally longitudinally of said shoe, an undetached strap substantially midway of said back transversely of said back and tongues stamped from said back between said straps and the edges of said back and spaced from said edges.
- 25 11. A back for a brake shoe having a four part lug formed of strips of metal drawn from said back.
- 30 12. A back for a brake shoe provided with a double key lug, the two parts of which are on opposite sides of the center line of said back, and each consisting of two tongues drawn longitudinally from the body of the back, the remaining back portions having a continuous arcuate form.
- 35 13. A back for a brake shoe provided with a double key lug, the two parts of which are on opposite sides of the center line of said back, said parts each consisting of two tongues drawn longitudinally from the ends of said back toward the center.
- 40 14. A back for a brake shoe provided with two longitudinally alined lugs each consisting of two tongues drawn longitudinally from the said back, the remaining portions of the said back constituting a continuous arcuate strip.
- 45 15. A back for a brake shoe provided with two longitudinally alined slotted lugs each consisting of two tongues drawn longitudinally from the said back, the remaining portions of the said back constituting a continuous arcuate strip.
- 50 16. A back for a brake shoe provided with two lugs longitudinally alined and each formed of two tongues drawn from the said back without bending the remaining portions of said back.
- 55 17. A back for a brake shoe provided with two lugs longitudinally alined formed of tongues drawn from the said back without bending the remaining portions of said back,
- 60 bending the remaining portions of said back, said lugs being divided longitudinally.
- 65 18. A back for a brake shoe provided with two lugs longitudinally alined formed of tongues drawn from the said back without bending the remaining portions of said back, said lugs being divided longitudinally and slotted.
- 70 19. A brake shoe having a four part lug consisting of integral untwisted tongues drawn from the body of the back.
- 75 20. A back for a brake shoe having a lug divided transversely and longitudinally.
- 80 21. A back for a brake shoe provided with a double holding lug, said lug consisting of four tongues drawn longitudinally from the body of the back, the space on opposite sides of said lug occupied originally by the metal of said tongues whereby the said back is fastened to the shoe body.
- 85 22. A back for a brake shoe provided with a holding lug, the space occupied by the fingers forming said lug providing four holes for fastening the back to the shoe body.
- 90 23. A back for a brake shoe consisting of a body strip provided with a key lug formed of two tongues drawn from the body of said strip in the same direction.
- 95 24. A back for a brake shoe provided with a key lug formed of tongues drawn from said back in the same direction.
- 100 25. A back for a brake shoe consisting of a body plate provided with a holding lug formed of tongues drawn from said plate in the same direction.
- 105 26. A back for a brake shoe provided with a key lug, said lug consisting of four untwisted fingers drawn longitudinally out of the body of the back without bending the remaining portions of the back.
- 110 27. A back for a brake shoe provided with a key lug, said key lug consisting of four untwisted fingers drawn longitudinally out of the body of the back, each forming a portion of said lug without bending the remaining portions of said back.
- 115 28. A back for a brake shoe provided with a key lug consisting of two pairs of oppositely extending untwisted fingers drawn longitudinally out of the body of the back.

In witness whereof, I hereunto subscribe my name this 14th day of April, A. D., 1916.

CHARLES W. ARMBRUST.
